UNITED STATES PATENT OFFICE.

JAMES H. PEARSON, OF BLOOMFIELD, INDIANA, ASSIGNOR TO WILLIAM S. BOGY, OF BLOOMFIELD, INDIANA.

JACK.

No. 851,313.

Specification of Letters Patent.

Patented April 23, 1907.

Application filed July 9, 1906. Serial No. 325,351.

To all whom it may concern:

Be it known that I, JAMES H. PEARSON, a citizen of the United States, residing at Bloomfield, in the county of Greene and State of Indiana, have invented certain new and useful Improvements in Jacks, of which the following is a specification.

My invention contemplates certain new and useful improvements in that type of lifting jacks and wire stretchers that operate upon what is known as the clutch-loop principle, the present embodiment of my invention partaking also to some extent of the characteristics of the ratchet type of jack, but this is only incidental to the main operative principle.

The object of my invention is to provide an improved lifting jack of this character which will be composed of comparatively few and simple parts and which will be durable, as well as efficient in operation and in which the parts may be readily detached from each other and as readily assembled without the necessity of any especial knowledge of machinery or without any machining of the parts. And a further object of the invention is to provide a jack of this character which will be absolutely devoid of nuts and bolts that are so liable to become loose and become lost, all the parts of my improved jack being susceptible to assembling without the necessity of any fastening means other than their own inherent construction and design as they come from the factory.

With these and other objects in view, as will more fully appear as the description proceeds, the invention consists in certain constructions, arrangements and combinations of the parts hereinafter fully described and particularly pointed out in the appended claims.

For a full understanding of the invention and the merits thereof and also to acquire a knowledge of the details of construction of the means for effecting the result, reference is to be had to the following description and accompanying drawings, in which:

Figure 1 is a perspective view of my improved lifting jack; Figs. 2 and 3 are detail sectional views on an enlarged scale, illustrating the parts in different positions; Fig. 4 is a side elevation of the two runners and operating parts, the standard of a portion of the operating lever being broken away; Fig. 5 is a

horizontal sectional view on the line $x-x$ of Fig. 4; Fig. 6 is a detail perspective view of the lower runner detached; Fig. 7 is a similar view of the wedge for the upper runner; and, Fig. 8 is a detail perspective view of the pitman detached.

Corresponding and like parts are referred to in the following description and indicated in all the views of the drawings by the same reference characters.

Referring to the drawings, the numeral 1 designates the standard of my improved jack, which is provided with a foot 2, a serrated or toothed edge 3, and a clevis 4 at its upper end. 5 designates the upper runner provided with a vertical opening by which it receives and encircles the standard and is mounted to slide longitudinally thereon, and 6 designates the lower runner of the jack, which is also mounted to slide longitudinally on the standard and also adapted to slightly tilt or cant thereon.

The upper runner 5 is provided in its front end with a circular opening 7 extending entirely therethrough, said opening communicating with a side slot or gap 8 which extends from one face of the runner but terminates short of the opposite face. Within the circular opening 7, a cam disc 9 is mounted to turn, said disc being provided with an opening 10 extending entirely therethrough, with an angularly notched side 11 and with a substantially crescent shape retaining member 12 which is preferably integral therewith. One edge 13 of this retaining member 12 constitutes a flange adapted to extend over the wall of the opening 7 and said retaining member is formed with a slot 11 and a lip 15 at one end of said slot. The cam disc 9 is preferably integrally formed on one end of the operating lever 16 of the jack, and said end of the lever is also provided with a flange 90 or enlarged edge 17 designed to coact with the flange or edge 13 to hold the cam disc 9 in place within the circular opening 7. The disc 9 is inserted within its opening 7 when the upper runner 5 is detached from the standard. By providing the gap or side opening slot 8 it is evident that the operating lever 16 may be turned around until the flange or edge 13 is opposite said slot 8, in which position the disc may be bodily entered into its opening 7. Then by turning the handle 16 and the disc 9, it is obvious that the flange 13 will engage with the bound-

105

ary wall of the opening 7 on one side, while the opposite flange 17 will engage with the said wall on the other side so as to maintain the disc properly mounted within its opening. The purpose of the slot 14 and the lip 15 of the crescent shape retaining member 12 will be hereinafter described. The operating lever 16 is provided with a preferably wooden handle portion 18 which is detachable therefrom and is wedged into secure engagement with the lever by having a slightly reduced end inserted within the loops 19 secured to or integral with the operating lever, as illustrated in the drawings.

5 The lower runner 6 is provided with a side opening slot 20, a transverse bore or opening 21 communicating with said slot at the lower end of the latter, and a socket 22 also communicating with the slot 20 at one end and designed to contain a helical expansion spring 23. The lower runner 6 is also formed at the rear side of its opening by which it receives the standard 1, with a toothed surface 24 adapted to engage with 25 the teeth 3 of the standard.

25 designates a pitman, which is provided at each end with a preferably integral wrist pin 26. The wrist pin at one end of this pitman is adapted to be journaled in the opening 10 in the disc 9 and is inserted in said opening through the slot 14 in the retaining member 12, when the disc 9 is turned around to bring such slot into complete coincidence with the opening 10. After said wrist pin is 30 in place, the disc 9 is turned around sufficiently far to bring the lip 15 of the retaining member over the outer face of the pitman and in all the subsequent operative movements of the disc in the actuation of the jack, 35 this lip will extend over the face of the pitman and thereby securely hold it in place. The wrist pin 26 at the opposite end of the pitman is seated in the bore or opening 21 of the lower runner 6 and the lower end of the 40 pitman works in the slot 20 of the lower runner and is engaged by the expansion spring 23. It will thus be seen that the spring 23, in its action, tends to cant the lower runner 6 on the standard, as illustrated in Fig. 2, so as 45 to cause the engagement of the toothed wall 24 with the teeth 3 of the standard, such engagement resulting in securely locking the runner to the standard as against downward displacement.

50 The upper runner 5 is provided at its rear side with a chamber 27, the rear wall of which is inclined, as shown, towards the toothed edge of the standard 1, said chamber having an opening 28 in its lower wall. A 55 wedge block or dog 29 is mounted within the chamber 27 and is provided with a toothed edge 30 intended for engagement with the toothed edge 3 of the standard. Said dog is also formed with a shoulder 31 and a spring 60 65 32 is mounted within the chamber 27 and

bears against the lower wall thereof and also against the shoulder 31 of the dog, so as to push the dog upwardly. This spring, coacting with the inclined wall of the chamber acts to force the dog 29 upwardly and inwardly toward the toothed edge 3 of the standard so that the toothed surface 30 of the dog will securely engage the teeth of the standard and prevent and hold the runner as against downward displacement. The wedge 70 75 block or dog 29 is provided at its rear or lower end with a lug 33 designed to engage the heel 34 of the upper runner, and a clevis or loop 35, or similar device is secured to the end of said lug so that the operator may pull 80 the dog downwardly and outwardly against the tension of the spring 32 and engage the lug 33 with the heel 34 of the runner so as to hold the dog in an inoperative position with its teeth and the teeth of the standard out of 85 engagement.

A lift bar 36 is provided at its upper end with an opening by which it is received upon and suspended from a journal pin 37 projecting from one face of the upper runner 5. The 90 lower end of this lift bar is provided with a bracket 38 designed for use when a low lift is desired or some horizontal pull upon a wire fence fabric or the like is necessary. The lower end of the lift bar 36 is also formed 95 with a laterally extending hook finger 39 adapted to spring around the front edge of the standard to secure the lower end of the lift bar to the standard. This securing action of the finger 39 is only as against an outward pull, it being understood that the lift bar 36 is free to slide in a true longitudinal direction with respect to the standard as the runners 5 and 6 climb the same. The lift bar 36 is formed at its journal end with a serrated cam surface 40 designed to coact with a clamping surface 41 projecting from one side of the upper runner 5 for the purpose of securing wire fence fabric or the like when it is desired to stretch the same. The upper runner 5 is formed below the clamping lug 41 with a laterally projecting ear or lug 42 adapted to bear against one edge of the lift bar 36 when the same is secured by the hook finger 39, and it will thus be seen that the lift 100 105 bar is held in a true longitudinal plane in the operation of the jack, all side lash or strain being avoided. Hence the lift bar 36 in the position just described, provides an increased bearing for the upper runner 5 and avoids 110 any sidewise strain upon said runner, the provision of the lift bar and its arrangement with the finger 39, the pin 37 and the ear 42 accomplishing the same bearing effect as if the upper runner 5 were extended from its 115 upper edge to the lower edge of the lift bar. In addition to its bearing function, as just described, the lift bar 36 may be sprung out of engagement with the standard 1 and turned 120 125 around on the pin 37 as a pivot and hooked 130

into a chain or clevis, on the upper end of the standard 1 for horizontal pulls as well as upward lifts.

In the practical use of the device to stretch wire, the lift bar 36 is unshipped, so to speak, from its engagement with the standard, and the wire is gripped between the lug 41 and the serrated cam surface 40 by swinging the lift bar on the pin 37 as a pivot. It is manifest that the wire may be then stretched by bracing the foot 2 against a fence post and working the handle 18 to cause the two runners to move along the standard.

From the foregoing description in connection with the accompanying drawings, it will be seen that my improved jack operates upon the clutch loop principle of alternately gripping members. To actuate the jack upwardly to raise a load, the wedge block or dog 29 is unshipped from its engagement between the lug 33 and heel 34 so as to give the spring 32 free play to wedge the dog upwardly in the chamber 27 and against the toothed edge 3 of the standard. By an up-and-down or pump-handle motion of the operating lever 16, it is evident that the runners will climb the standard. Assuming that the handle of the operating lever is raised into a substantially vertical position, the notched side 11 of the disc 9 will then bear against the outer edge of the pitman 25 and force the pitman inwardly so as to swing the lower runner 6 to a true horizontal position with respect to the standard, and this will result in bringing the smooth wall 24^a of the lower runner against the smooth edge of the standard and in throwing the toothed wall of the runner out of engagement with the toothed edge of the standard, as illustrated in Fig. 3. Hence with the parts in this position, the lower runner 6 is free to slide upwardly on the standard and this upwardly sliding movement is effected, obviously, by the relative position of the disc 9 in its bearing opening 7, for it will be seen with reference to said Fig. 3, that the eccentric opening 10 of the disc, in which the upper wrist pin 26 of the pitman is mounted has swung around and upwardly to draw the pitman and consequently the lower runner, in an upward direction. During this movement, the upper runner has been held stationary as against downward displacement by means of the engagement between the teeth of the dog 29 and one edge of the standard 1. By then lowering the handle, or operating lever, it is obvious that the notch 11 of the disc 9 will be carried out of engagement with the pitman 29 and thereby allow the spring 23 to cant the lower runner to the position shown in Fig. 2 with the toothed wall 24 and the toothed edge of the standard in engagement thereby locking the lower runner to the standard. This same movement will manifestly move the upper runner 5 upwardly on the standard, as the

lower wrist pin 26 of the pitman will act as a fulcrum for the toggle-like movement of the disc 9 and pitman, the said upward movement of the upper runner being accommodated or permitted by the teeth 30 of the dog 70 29 sliding upon the teeth 3 of the standard. Hence it will be seen that by this pump handle motion of the lever, first one runner will clutch the standard and then the other runner will clutch, one runner rising while the other runner remains stationary, and each in turn supporting the other in the climbing action. To climb down the standard, the weight is first thrown on the upper runner and the handle manipulated so as to lower the 80 lower runner to its full extent; the dog 29 is then pulled downwardly and the handle manipulated so as to let the upper runner slide downwardly as far as possible, while the weight is upon the lower runner, the dog is 85 then freed so as to hold the upper runner stationary while the lower runner slides down, and so on until the limit of the lowering movement has been reached. To let both runners slide quickly down the standard, it is 90 only necessary to lock the dog 29 in its inoperative position and to then raise the operating lever to a full vertical position which will let the lower edge of the upper runner down upon the upper edge of the lower runner and 95 this contact between the two edges of the runners will result in forcing the lower runner to true horizontal position with respect to the standard, with its teeth disengaged from the teeth of the standard, and obviously both 100 runners may then be slid quickly down the latter.

It will be seen that my improved invention enables the parts of my improved jack to be so formed or made as to do away entirely 105 with rivets, bolts, screws, or similar fastening devices. The parts need no machine work to assemble them and may readily be assembled and taken apart again by any one of reasonable intelligence, and when assembled 110 it is obvious that a strong and durable structure is produced.

Having thus described the invention, what is claimed as new is:

1. A device of the character described, 115 comprising a standard, upper and lower runners mounted upon said standard, means for effecting a climbing action of the runners on the standard, and a lifting bar carried by the upper runner and having a sliding engagement with the standard below the lower runner.

2. A device of the character described, 125 comprising a standard, upper and lower runners mounted upon said standard, means for effecting a climbing action of the runners on the standard, and a lifting bar carried by the upper runner and having a detachable sliding engagement with the standard.

3. A device of the character described, 130

comprising a standard, upper and lower runners mounted upon said standard, means for effecting a climbing action of the runners upon the standard, and a lifting bar carried by one of said runners and provided at its lower end with a laterally extending hook finger adapted to spring around the edge of the standard below the lower runner.

4. A device of the character described, comprising a standard, upper and lower runners mounted upon said standard, means for effecting a climbing action of the runners on the standard, and a lifting bar carried by the upper runner and having a sliding engagement with the standard below the lower runner, said lifting bar being provided with a bracket, as and for the purpose specified.

5. A device of the character described, comprising a standard, upper and lower runners mounted upon said standard, means for effecting a climbing action of the runners on the standard, and a lifting bar pivotally mounted upon the upper runner and arranged for detachable sliding engagement with the standard, said lifting bar being provided at its pivoted end with a serrated cam surface, the upper runner being provided with a lug adapted to coact with said cam surface.

30 6. A device of the character described, comprising a standard, upper and lower runners mounted upon said standard, means for effecting a climbing action of the runners on the standard, and a lifting bar pivotally mounted at one end upon the upper runner and adapted for sliding engagement with the standard at its other end, the upper runner being provided with a laterally projecting ear adapted to engage the lifting bar intermediate its ends, for the purpose specified.

45 7. A device of the character described, comprising a standard, upper and lower runners adapted to climb said standard, the upper runner being provided with a bearing opening, and a side slot opening thereinto, a disc mounted in said bearing opening and provided with an eccentric opening, a pitman journaled at one end in the opening in the disc and also journaled in the lower runner, and an operating lever operatively connected to said disc, the said disc being provided with a retaining member having a flange designed to engage the boundary wall of the bearing opening whereby to retain the disc therein.

55 8. A device of the character described, comprising a standard, upper and lower runners mounted to climb the standard, the upper runner being provided with a bearing opening, a disc mounted in said opening, means for turning said disc, the disc being provided with an eccentric opening, a pitman journaled in said eccentric opening and in the lower runner, and a retaining member 60 on said disc, said retaining member being

formed with a rib adapted to extend over the pitman to hold the same in place.

9. A device of the character described, comprising a standard, upper and lower runners mounted to climb the standard, the upper runner being provided with a bearing opening, a disc in said opening, means for turning said disc, a pitman journaled in the lower runner and journaled eccentrically in the disc, and a retaining member on the disc, 75 said retaining member being formed with a slot adapted to receive the upper end of the pitman, and a rib designed to extend over the pitman to hold the same in place.

10. A device of the character described, comprising a standard, upper and lower runners mounted to slide on said standard, the lower runner being adapted to tilt on said standard into clutching engagement therewith, a pitman operatively connecting the two runners, an operating disc mounted in the upper runner and in which the upper end of the pitman is journaled eccentrically, and means for turning said disc, the disc being provided with a notch adapted to be brought into engagement with the upper end of the pitman and arranged to throw the lower end of the pitman inwardly, whereby to swing the lower runner out of locking engagement with the standard.

95 11. A device of the character described, comprising a standard, upper and lower runners mounted to slide on said standard, the lower runner being arranged to tilt on said standard into clutching engagement therewith, a pitman operatively connecting the runners, a cam disc mounted in the upper runner and in which the upper end of the pitman is eccentrically journaled, the said disc being provided with a notch adapted to engage the upper end of the pitman for the purpose specified, means for turning said disc, and a spring mounted in the lower runner and bearing against said pitman.

100 12. A device of the character described, comprising a standard, upper and lower runners mounted to slide on said standard, the lower runner being arranged to tilt on said standard into clutching engagement therewith and provided with a side opening slot 105 and with a bore and a socket communicating with said slot, a pitman operatively connecting said runners, one end of said pitman being seated in said slot of the lower runner and provided with a wrist pin journaled in the bore of said runner, means for actuating said pitman to alternately move the two runners, and a spring in the socket of the lower runner, said spring engaging said pitman for the purpose specified.

125 13. A device of the character described, comprising a standard, upper and lower runners mounted to climb the standard, a disc mounted in the upper runner and provided with an eccentric opening, means for turning 130

said disc, and a pitman provided at each end with an integral wrist pin, one of said wrist pins being journaled in the eccentric opening in the disk and the other journaled in the 5 lower runner.

14. A device of the character described, comprising a standard, upper and lower runners mounted to slide on said standard, the lower runner being adapted to tilt on the 10 standard into clutching engagement therewith, a pitman operatively connecting said two runners, means for locking said pitman, the upper runner being provided at its rear side with a chamber having an inclined wall 15 and a lower opening and the upper runner being provided with a heel at one side of said opening, and a wedge block mounted in said chamber and spring pressed toward the standard, said wedge block having one end 20 extending out through the opening and being provided with a lug arranged for engagement with the said heel, as and for the purpose set forth.

15. A device of the character described, 25 comprising a standard, upper and lower runners mounted upon said standard, means for effecting a climbing action of the runners on the standard, and a lift bar pivotally mounted on one of said runners and arranged for 30 detachable sliding engagement with the standard, the said runner and lift bar being

arranged to constitute a wire clamp, as and for the purpose set forth.

16. A device of the character described, comprising a standard, upper and lower runners mounted upon said standard, the lower runner being provided with a side opening 35 slot and a bore communicating with said slot, a pitman having its lower end detachably seated in said slot and provided with a 40 wrist pin mounted in said bore, and a detachable operative connection between the upper end of said pitman and the upper runner.

17. A device of the character described, 45 comprising a standard, upper and lower runners mounted upon said standard, the lower runner being provided with a side opening slot and a bore and a socket both communicating with said slot, a pitman having its 50 lower end seated in said slot and provided with a wrist pin mounted in said bore, a spring in said socket adapted to bear against said pitman, and a detachable operative connection between the upper end of said pit- 55 man and the upper runner.

In testimony whereof I affix my signature in presence of two witnesses.
